UNITED STATES PATENT OFFICE.

HENRY MINTZ, OF ROXBURY, MASSACHUSETTS, ASSIGNOR TO NEW ENGLAND BEDDING COMPANY, OF BOSTON, MASSACHUSETTS, A CORPORATION OF MASSACHUSETTS.

FOLDING BED.

Application filed September 23, 1922. Serial No. 590,036.

To all whom it may concern:

Be it known that I, HENRY MINTZ, a citizen of the United States of America, and resident of Boston, Roxbury, in the county 5 of Suffolk and State of Massachusetts, have invented new and useful Improvements in Folding Beds, of which the following is a specification.

This invention pertains to folding beds 10 of the davenport type and relates more particularly to improvements in the means for holding the swinging mattress supporting frame in substantially vertical position to form a back-rest when the device is used as 15 a davenport.

When it is desired to swing the back-rest downwardly into alignment with the seat to form a bed it is ordinarily necessary for the user to manipulate bolts or catches, or to 20 impart a quick forward and back jerk to the back member in order to disengage it from the retaining means employed, and then as the back approaches horizontal position to unfold the supporting legs which are hinged 25 to its rear side. The object of the present invention is to simplify the above operation by relieving the user of the necessity of manipulating retaining catches or otherwise disengaging the back-rest retaining means 30 as an independent step in converting the device from a davenport couch into a bed.

To this end the present invention comprises connections between the supporting legs for the back-rest and the back-rest retaining means so arranged that unfolding of the legs automatically disengages the retaining means, permitting the back-rest to swing freely down into horizontal position. To permit of this result the retaining means 35 is so devised that when released as above described it is positively prevented from re-engagement with its cooperating parts until the legs have again been folded. In the accompanying drawings one embodiment of 40 means useful in attaining the above object is illustrated by way of example and in such drawings:

Fig. 1 is an end elevation, partly broken

away and partly in section, illustrating the device of the present invention as arranged 50 to form a davenport couch;

Fig. 2 is an end elevation of the device showing the back-rest as folded down upon the bottom frame in position for shipment;

Fig. 3 is a fragmentary end elevation 55 showing the parts as positioned to permit the back-rest to be swung rearwardly to form a bed;

Fig. 4 is a fragmentary end elevation showing the back-rest as occupying a horizontal position to form a bed; and 60

Fig. 5 is a fragmentary horizontal cross section on the line 5—5 of Fig. 4.

The folding bed constructed in accordance with the present invention comprises 65 end frames such as 1, of which but one is herein illustrated, it being understood that the other is in all respects similar to that illustrated, and that the attachments and other movable parts hereinafter specifically 70 described are duplicated at the opposite end of the bed. Each end frame comprises legs 2—3, and the front legs and rear legs of the two end frames are preferably united by longitudinal bars 4. The mattress supporting frame is also secured to the end frames at a suitable height from the floor such mattress supporting frame comprising a stationary part and a movable part, the latter 75 constituting the back-rest when the device 80 is employed as a davenport couch. The stationary part of the mattress supporting frame comprises end members such as 5 united at opposite ends to the front and rear legs 2, 3 respectively. Each end member is 85 preferably formed of angular iron and comprises the vertical flange 6 and the horizontal flange 7. The movable portion of the mattress supporting frame comprises end members such as 8, also formed from angular iron, having the horizontal flange 9 and the vertical flange 10. The flanges 7 and 10 are united by means of hinges such as 11 90 permitting the movable frame to swing relatively to the fixed portion of the frame. 95 The movable part of the mattress support-

ing frame or "back-rest" as it is hereinafter termed, is provided at each end with a supporting leg such as 12, pivotally secured to the flange 10 at the point 13. For holding the leg in operative position a folding brace comprising the members 14 and 15 is provided, the member 14 being pivoted to the leg 12 at 16, and the member 15 being pivoted to the flange 10 at 17. The members 14 and 5 are united by a pivot pin 18, the joint between them being preferably of the self-locking type which is commonly used in step ladder braces.

For holding the back-rest frame in upright position, as indicated in Fig. 1, a releasable latch device or brace 20 is provided. This latch member or brace is furnished at one end with a curved portion 21 which passes down through a slot 22 in the flange 9 of the back-rest frame and is provided with a projecting pin 23 which slides freely in an elongate 24 in the vertical flange 10. The opposite end of the brace 20 is provided with a curved tail 25 which extends downwardly through an elongate slot 26 in the flange 7 of the stationary part of the frame. The tail 25 is of sufficient length to prevent disengagement of the brace or latch member from the slot 26 when the back-rest frame is moved to the position shown in Fig. 4. At a point adjacent to the junction of the tail member 25 with the main body of the latch member or brace, the latter is provided with a notch 27 in its lower edge adapted to engage the edge 28 of the slot 26, the engagement of the notch with such edge serving to hold the back-rest in the position indicated in Fig. 1. The upper edge of the notch 27 is defined by one side 29 of the substantially triangular lug or projection 30 outstanding from the lower edge of the brace or latch member. The opposite side 31 of such triangular projection constitutes a cam element the purpose of which will be described hereinafter. A link 32 is pivotally connected at the point 33 to the folding brace member 15 and the opposite end of this link is secured to the pin 23 which projects from the rear end of the latch member 20.

When the device is to be used as a davenport couch the legs 12 are folded against the back rest as indicated in dotted lines in Fig. 1, and such folding of the legs serves to draw the link 32 upwardly, thereby causing the pin 23 to occupy a position at the upper end of the slot 24 as shown in Fig. 1. In this position, engagement of the notch 27 with the edge 28 of slot 26 serves positively to hold the back-rest in upright position, the engagement of the side 29 of projection 30 with the upper surface of flange 7 serving to steady the device and to prevent accidental disengagement of the notch from the edge 28.

If it be desired to fold the back-rest down-

wardly on the stationary frame as indicated in Fig. 2, it is merely necessary to pull the back-rest forwardly thereby causing the brace 20 to slide forwardly until the lug 30 slips over the edge 28, whereupon the latch moves downwardly through the slot 26 to the position shown in Fig. 2. On the other hand if it be desired to convert the device from a davenport couch to a bed, the user first unfolds the legs 12, causing them to occupy the position shown in Fig. 3. This movement of the legs causes the link 32 to move downwardly until the pin 23 occupies the lower end of the slot 24. This movement of the pin pushes the latch 20 bodily in a forward direction, disengaging the notch 27 from the edge 28 of flange 7 and permitting the triangular lug 30 to assume the position shown in Fig. 3, wherein the cam surface 31 is brought into engagement with the edge 28. The back-rest may now be swung freely downward into the position shown in Fig. 4, the cam surface 31 riding over the edge 28 and lifting the projection 30 with the brace 20 so as to prevent accidental engagement of the notch 27 with the edge 28 during such movement of the back-rest. When it is desired again to employ the device as a davenport couch, the legs 12 are swung downwardly, thus moving the pin 23 to the upper end of slot 24, and upon raising back-rest frame to a position slightly forward of that shown in Fig. 1, the notch 27 may again be engaged with the edge 28, thus holding the parts in the desired position.

While the arrangement herein shown is preferred, it is also contemplated that various changes and rearrangements in the parts may be made from time to time as may be necessitated by the demands of the trade without departing from the spirit of the present invention.

What I claim and desire to secure by Letters Patent of the United States is:—

1. A device of the character described comprising a bottom frame and a back-rest frame hinged thereto, a latch pivotally secured to one of said frames and having a body portion provided with a securing notch and with a rigid fulcrum projection immediately adjacent said notch, and means for rocking the latch on the fulcrum projection to control the engagement of the notch with an element of the other of said frames.

2. A device of the character described including a pair of hingedly connected frames, each having a slot therein, and means for locking said frames in relatively adjusted position, said means comprising a latch having a pin fitting the slot of one of the frames and having a notched portion engageable in the slot of the second of said frames, said latch having a fulcrum portion adjacent the notch therein, and means for

shifting the pin in its slot to selectively present the notch or the fulcrum of the latch to an element of the second of said frames.

3. A folding bed of the davenport type having a bottom frame and a back-rest hinged thereto, a latch member movably connected to the back-rest and having a notch engageable with an element of the bottom frame for holding the back-rest in upright position, a supporting leg hinged to the back-rest, and means comprising a link connecting the leg and latch member whereby movement of the leg to operative position serves to disengage the notch in the latch member from the cooperating element of the frame.

4. A folding bed of the class described comprising a fixed frame member having an elongate slot therein, a member hinged to the fixed member, a brace connected to the hinged member and extending through the slot in the fixed frame member, said brace having a latching notch engageable with the edge of the slot, a leg pivotally secured to the hinged frame member, and a means comprising a link connecting the leg and brace whereby movement of the leg to operative position imparts bodily movement to the brace to disengage its notch from the edge of the slot.

5. A folding bed of the class described comprising a fixed frame member having an opening therethrough, a second frame member pivotally secured to the first member, a latch connected to the movable member and extending through the opening in the fixed member, said latch having a notch for engagement with the edge of the opening, a leg hinged to the second frame, and means connecting the leg with the latch whereby movement of the leg to operative position disengages the latch notch from the edge of the opening.

6. A folding bed of the class described comprising a pair of frame members hinged together, one of said members having a slot therein, a latch member having one end extending through the slot and provided with a notch engageable with the edge of the slot, means connecting the opposite end of the latch member to the other frame member for limited sliding movement relatively thereto, and means for moving the last named end of the latch member to disengage its notch from the edge of the slot.

7. A folding bed of the davenport type having a bottom frame and a back-rest frame, a latch member provided adjacent to one of its ends with an element engageable with an element of the bottom frame for retaining the back-rest frame in upright position, a pin secured in the opposite end of the latch member and engaging the slot in the back-rest frame, and means for moving said pin longitudinally of the slot to dis-

engage the latch element from the cooperating element of the bottom frame.

8. A folding bed of the davenport type having a bottom frame and a back-rest frame hinged thereto, a latch member having one end extending through an opening in the bottom frame and provided with an element engageable with the latter frame, a pin projecting from the other end of the latch member and slidably engaging an elongate slot in the back-rest frame, a leg hinged to the latter frame, and means operatively connecting said leg to said projecting pin.

9. A folding bed of the davenport type having a bottom frame and a back-rest hinged thereto, a latch member having a notch adjacent to one end for engagement with an element of the bottom frame, guide means associated with the back-rest frame permitting limited bodily movement of the opposite end of the latch relatively to the latter frame, a leg hinged to the back-rest frame, a foldable brace for the leg, and a link connecting one element of said brace with the last named end of the latch.

10. A device of the character described including a pair of relatively foldable frames, a latch carried by one of the frames and having interlocking engagement with the other frame, said latch being releasable by relative movement of the frames, and means for shifting the latch with respect to both of said frames to render the same inoperative.

11. A folding bed of the davenport type having a bottom frame member provided with a slot therethrough, a second frame member hinged to the first member, a latch connected at one end to the second frame member and having its opposite end projecting through the slot in the bottom frame member and provided with a notch engageable with the edge of the slot, and a lug projecting from the latch adjacent to the notch to prevent untimely engagement of the notch with the edge of the slot.

12. A davenport bed comprising a bottom frame member having an elongate slot therein, a second frame member hinged to the first, a latch slidably connected at one end to the second frame member and having its other end projecting through the aforesaid slot, the latter end of the latch having a notch engageable with the edge of the slot, a lug projecting from the latch adjacent to its notch provided with a cam surface engageable with the edge of the notch to prevent untimely engagement of the notch therewith, and means for moving that end of the latch connected with the second frame member for disengaging the notch from the edge of the slot.

13. A davenport bed comprising a bottom frame member and a second frame member

hinged thereto, and a latch for normally retaining said hinged member in upright position comprising an elongate member having curved end portions, one of said end portions projecting through a slot in the first frame member and the other through a slot in the second frame member, means slidably connecting the latter end to the hinged frame member, means carried by the

first named end of the latch for engagement 10 with the end of the slot in the bottom frame member, and means for regulating the position of the opposite end of the latch relatively to the second frame member.

Signed by me at Boston, Massachusetts, 15 this 21st day of September, 1922.

HENRY MINTZ.
